(57) **CLAIM**

The ornamental design for a decorative object made of glass;
natural and artificial gem stone, as shown and described.

DESCRIPTION

FIG. 1 is a bottom view of a decorative object made of glass;
natural and artificial gem stone;

FIG. 2 is a right side view of the gem according to the first
embodiment;

FIG. 3 is a front view of the gem according to the first
embodiment;

FIG. 4 is a left side view of the gem according to the first
embodiment;

FIG. 5 is a rear view of the gem according to the first
embodiment;

FIG. 6 is a top view of the gem according to a first
embodiment;

FIG. 7 is a front side perspective view of the gem according
to the first embodiment;

FIG. 8 is a rear side perspective view of the gem according
to the first embodiment;

FIG. 9 is a bottom view of the gem according to the second
embodiment;

FIG. 10 is a right view of the gem according to the second
embodiment;

FIG. 11 is a front view of the gem according to the second
embodiment;

FIG. 12 is a left side view of the gem according to the second
embodiment;

FIG. 13 is a rear view of the gem according to the second
embodiment;

FIG. 14 is a top view of the gem according to the second
embodiment;

FIG. 15 is a front side perspective view of the gem according
to the second embodiment; and,

FIG. 16 is a rear side perspective view of the gem according
to the second embodiment.
